UNITED STATES PATENT OFFICE.

GEORGE H. SMITH, OF LOWELL, MASSACHUSETTS.

IMPROVED LAST-HOLDER.

Specification forming part of Letters Patent No. 39,839, dated September 8, 1863.

To all whom it may concern:

Be it known that I, GEORGE H. SMITH, of Lowell, in the county of Middlesex and State of Massachusetts, have invented a new and Improved Last-Holder for Shoe-Makers' Use; and I do hereby declare that the following is a full, clear, and exact description of the same, reference being had to the accompanying drawings, making a part of this specification, in which—

Figure 1 is a vertical central section of my invention, taken in the line *xx*, Fig. 2; Fig. 2, a plan or top view of the same; Fig. 3, an inverted plan of a portion of the top plate of the device; Fig. 4, a detached view of a portion of the last-adjusting mechanism.

Similar letters of reference indicate corresponding parts in the several figures.

This invention relates to a new and improved device for holding lasts designed for the use of shoe-makers.

The object of the invention is to obtain a device for the purpose specified, which will, by a simple adjustment, hold the last securely in position, and at the same time admit of the latter being inclined at any desired angle and turned or revolved as required while being thus inclined.

To enable those skilled in the art to fully understand and construct my invention, I will proceed to describe it.

A represents a wooden post or stand secured to a base, *B*, which is screwed or bolted to any proper support, and *C* is a metal cap-piece of annular form, provided with a cross-bar, *a*, and screwed or bolted firmly to the top of the post *A*. The post *A* and base *B* are both hollow, or have openings *b* made vertically in them, in which a bar, *D*, is fitted, said bar being perforated with holes *c* at suitable distances apart, and passing through the center of the cross-bar *a* and between two vertical lugs, *d d*, thereon, as shown in Fig. 1.

E represents a horizontal bolt, one end of which is fitted in one of the lugs *d*, the opposite end passing through a guide or bearing, *e*, attached to or cast with the cap-piece *C*. On this bolt *E* there is placed a spiral spring, *F*, which has a tendency to keep the bolt *E* in any one of the holes *c* of the bar *D* to hold the latter at any desired height. The outer end of the bolt *E* is provided with a head, *f*, which is fitted in a recess in the cap-piece, so

that it may, when necessary, be grasped by the fingers and the bolt drawn outward to liberate the bar *D* and admit of the latter being adjusted higher or lower, as desired.

To the upper end of the bar *D* there is attached by a pin or pivot, *g*, a screw-bolt, *G*, which is allowed to turn freely on the pin or pivot *g*, and to the cap-piece *C* there is attached by hinges or joints *h* a circular metal plate, *H*, of the same diameter as the cap-piece, and through the center of which the bolt *G* passes. The center of the plate *H*, at its upper surface, is provided with a circular hub, *i*, on which a circular metal plate, *I*, is fitted and allowed to turn freely. This plate *I* is of the same diameter as the plate *H* and cap-piece *C*, and the bolt *G* passes through the center of *I* and has nuts *j* fitted upon it, which secure *I* on *H*. The upper surface of the plate *I* has two parallel vertical plates, *J J*, cast with it, the inner surface of said plates extending from the center of *I* to its periphery. The inner surfaces of these plates are grooved vertically their whole length, as shown at *k*, to receive a vertical bar, *K*, which has a toe-rest, *L*, at its upper end. The bar *K* may be fitted in any of the grooves *k* to suit the length of the last, which is designated by *M*. The toe of the last *M* is fitted on the rest *L*, and the back part is fitted on the upper end of a bent lever, *N*, which is provided at both sides of its angles with journals *l l*, the latter fitting in bearings *m* on the upper surface of the plate *I*. The lower end of the lever *N* is connected by a link, *O*, with one end of a lever, *P*, which is underneath the plate *I*, and is attached thereto by a fulcrum-pin, *u*, which passes through a pendent projection, *o*. (See Fig. 3.) The opposite end of the lever *P* is connected by a link, *Q*, which passes up through the plate *I*, and has a screw-thread cut upon it to receive a thumb-nut, *R*.

From the above description it will be seen that by screwing down the thumb-nut *R* the last *M* will be firmly secured in position, the toe of the last being pressed snugly on the toe-rest *L*; and it will also be seen that when the plate *H* is allowed to rest on the cap-piece *C* in a horizontal position the last *M* will be in a horizontal position, and that by drawing out the bolt *E* and liberating the bar *D* and raising the same the plates *H* *I* will also be raised in a more or less inclined position, in

consequence of the plate H being connected by hinges to the cap-piece C and the bolt G being allowed to turn on its pin or pivot *g*. Thus the last M may be adjusted in a more or less inclined position and the plate I turned, and also the last while thus inclined, so as to bring the work in any desired position required by the shoe-maker.

Having thus described my invention, what I claim as new, and desire to secure by Letters Patent, is—

1. The sliding bolt E, in connection with

the perforated bar D, arranged substantially as shown, for holding the last at a greater or less degree of inclination, as may be required.

2. The levers N P, link O, screw-link Q, and nut R, all arranged substantially as shown, for the purpose of securing the last in proper position, as set forth.

GEO. H. SMITH.
